(57) **CLAIM**

The ornamental design for a crown protector, as shown and described.

DESCRIPTION

FIG. 1 is a front perspective view of the crown protector as used on a watch

FIG. 2 is a front view of the crown protector

FIG. 3 is a side view of the crown protector

FIG. 4 is a top view of the crown protector

FIG. 5 is a bottom view of the crown protector

FIG. 6 is a back view of the crown protector; and,

FIG. 7 is a front perspective view of the crown protector in an open mode.

The broken lines disclose the environment with which the design is associated and form no part of the claimed design.
